UNITED STATES PATENT OFFICE.

MORLAND MICHOLL DESSAU, OF LONDON, ENGLAND.

WASHBOARD.

Application filed October 29, 1923. Serial No. 671,559.

To all whom it may concern:

Be it known that I, MORLAND MICHOLL DESSAU, a citizen of the United States of America, residing at London, England, have ⁵ invented Improvements in or Relating to Washboards (for which I have filed application in Great Britain November 22, 1921, No. 31,263), of which the following is a specification.

¹⁰ This invention relates to washboards and has for its object to provide an improved surface whereon to support clothes and other articles whilst soaping or treating the same and over which the clothes are afterwards ¹⁵ rubbed.

As is now well known numerous proposals have been made from time to time to use in washing apparatus coverings, sometimes perforated, constituted of sundry material including rubber which has been treated as by moulding, puckering, folding or the like, to produce studs, bristle-like surfaces, diamond and other shaped projections or broken frictional surfaces.

²⁵ In contradistinction to the foregoing, which are necessarily relatively expensive forms of covering, a washing board according to the present invention comprises a thin flexible sheet of what is most frequently ³⁰ termed crêpe or smoked sheet rubber meaning thereby such raw rubber sheet of commerce as has a highly roughened surface and can be used directly as a covering without having to be subjected to any mechanical ³⁵ treatment to produce the required frictional properties provided it be held taut by at least two of its opposite edges. The rubber, which is thin, is vulcanized by a cold process such as the Peachey process. If desired the ⁴⁰ sheet rubber may be backed or reinforced with a substantially non-stretching fabric; and it may be perforated as shown at ^{f'} in Fig. 3.

⁴⁵ A covering of this kind whether it be stretched over a flat or corrugated surface or supported in other appropriate way will be found to produce an effective lather and enable dirt to be quickly and easily removed without undue wear upon the washing. The ⁵⁰ covering is exceedingly cheap, can be thus readily replaced when worn and may be applied to the board in various ways. Conveniently both sides of a board may be covered by a single sheet of the material passed over

an adjustable roller or stretching member ⁵⁵ arranged in the bight formed by securing two opposite edges to the board.

The wash boards may be so constructed as to have pockets or recesses to hold the soap or in another construction these pockets or ⁶⁰ the like may contain the soap or the like so as to give a continuous soaping and lathering to the clothes without waste.

In the accompanying drawings, Fig. 1 is a perspective view of a portable washboard ⁶⁵ showing one way of carrying out the invention. Fig. 2 is a section through a portion thereof and Fig. 3 is a similar section of a modification. Figs. 4, 5, 6 and 7 are fragmentary views illustrating other modifications applicable to a portable washing board. Fig. 8 is a detail perspective view showing a broken-away portion of a washboard having a covering of crêpe sheet rubber and a ⁷⁰ backing or reinforcing layer of substantially non-stretching fabric applied thereto.

As shown in Fig. 1 a sheet ^a of crêpe rubber is attached at one end ^b to the lower rail ^c and after passing around a roller ^d is attached at the opposite end to the other ⁸⁰ side of the rail ^c. ^e is the backing board which in Fig. 2 is shown as having one face plain and the other face corrugated. Fig. 3 illustrates the provision of two soap containing pockets ^f in a board having both ⁸⁵ faces plain and a covering of perforated crêpe sheet rubber. The roller ^d has pivots which, extending through slots ^g in the legs of the washboard, are mounted in eye screws ⁹⁰ ^h so that with the aid of wing nuts ⁱ the roller can be adjusted to tighten or slacken the rubber sheeting ^a.

The rubber may be first cured and afterwards affixed as a sheet to the face of a board as in Fig. 4, by means such as a framing of ⁹⁵ strips ^j which may be either plain or rubber covered. Or as shown in Fig. 5 the board may in addition be formed with holes such as ^k filled with rubber and to which the crêpe or smoked sheet facings are affixed. If as in Fig. 6 the holes be filled with plugs ^m of a length sufficient to project beyond the board the crêpe rubber facing when affixed thereto will be supported clear of the board and thus act like a pneumatic cushion. As ¹⁰⁰ a further modification shown in Fig. 7 crêpe rubber rolled into cord form ⁿ may be affixed to a board faced with rubber as in Fig. 4 by

lacing the same through holes therein the pitch of the holes being chosen to enable the rubber to be exposed in any desired lengths. The rubber cord or roll may be united to the 5 rubber sheet *a* in any suitable way.

What I claim is:—

1. A washing board comprising a support, and a covering of thin crêpe sheet rubber having a rough surface held taut upon the 10 support by at least two of its opposite edges.

2. A washing board comprising a support, and a covering of thin crêpe sheet rubber having a rough surface held taut upon the support by at least two of its opposite edges 15 said rubber sheet being vulcanized.

3. A washing board comprising a support, having a cavity therein adapted to receive a detergent, and a covering of thin crêpe sheet rubber having perforations therein and 20 stretched taut upon the support and covering the detergent cavity.

4. A washing board comprising a member having two sides serving as support surfaces and a covering of thin crêpe sheet rubber

having a rough surface stretched over both 25 sides of the support.

5. A washing board having two sides serving as supports, a thin flexible sheet of raw rubber attached at one edge to one side and at the opposite edge to the other side of 30 the said washboard, the fastened edges being adjacent leaving a bight in the rubber sheet at one end of the washboard and means arranged in the bight whereby the rubber sheet can be stretched. 35

6. A washing board, both sides of which are adapted to serve as supports, a single sheet of crêpe rubber attached at one edge to one edge of one side of the support passed over the opposite edge of the support and 40 attached to the other side of the support leaving a bight in the rubber sheet, a stretching roller arranged in the bight aforeaid and means for adjusting the position of said roller. 45

Signed at London, England, this 19th day of October 1923.

MORLAND MICHOLL DESSAU.
